UNITED STATES PATENT OFFICE

HERBERT M. KNIGHT, OF MONTCLAIR, NEW JERSEY

PILING

Application filed September 16, 1927. Serial No. 219,883.

This invention relates to improvements in piling and is more especially related to sheet piles in which the various piles are united by means of keys.

5 The objects of the invention are to provide over-lapping pre-cast piles; to provide means for securing over-lapping piles together; to provide means for preventing pre-cast piles from spreading away from each other 10 in any direction; to provide keys for holding the piles together which are independent of the piles until inserted in place; to provide key-ways in the overlapping piles for receiving said keys; to enable wash-pipes to be employed in connection with said piles; to enable the wash-pipes to be employed during 15 hammering of the piles; to secure simplicity of construction and operation, and to obtain other advantages and results as may be 20 brought out in the following description.

The accompanying drawings, Figures 1 to 7, inclusive, illustrate the usual and preferred embodiment of the invention, but are not to be considered as inclusive of all forms 25 in which the invention may be embodied, nor as exclusive of forms other than those indicated.

I illustrate my invention by the accompanying drawings in which Figure 1 is a 30 cross-section of the head of a pile on the line 1-1 of Fig. 3.

Figure 2 is a cross-section of the body of said pile on the line 2-2 of Fig. 3.

Figure 3 is a face view of a pile on the 35 line 3-3 of Fig. 1.

Figure 4 is a longitudinal section of a pile on the line 4-4 of Fig. 3.

Figure 5 is a cross-section through the heads of an assembly of such pre-cast piles.

40 Figure 6 is a double cross-section at a joint between such assembled piles, one partial section being through the head of the pile, at such a joint, and the other said partial section being through the body of said pile.

45 Figure 7 is a section through the body of a curvilinear pile.

One of the primary purposes in driving a line of pre-cast sheet piling is to secure a wall, which, while in a measure flexible, shall pre- 50 serve a fairly accurate alinement and be sub-

stantially water-tight. These objects become increasingly important when such sheet piling is to act as the core of an embankment or in other position where its duration is permanent rather than temporary. Various means are employed to obtain these desirable ends, by interlocking, as in the case of steel sheet piling, or by "triple-lap" as in the case of wooden piling. In the case of sheet piling made of concrete such interlocking is difficult and lapping, as such, is rarely attempted. This invention secures the advantages of interlocking and lapping without the defects inherent in both of these methods as at present practiced.

A pile is cast of a generally rectangular cross-section. This cross section is not of uniform thickness, strengthening ribs being cast at certain points. Between the thickened edges of the piles and these strengthening ribs, depressions are formed materially reducing the thickness, weight and cost of the piles, without decreasing the strength thereof for the purposes for which they are employed. The thickened edges are not 70 symmetrical with reference to a longitudinal mid plane of said pile but are off-set oppositely from such medial plane. Such off-setting produces rabbets at either end of said mid section, the depth of such rabbet being 75 such as will receive the rabbet edge of an adjacent pile. On the lapping faces of these said edges grooves or key-ways have been formed said key-ways of juxtaposed edges of adjacent piles, being in alinement. A key, 80 either solid or poured, being introduced into said alined key-ways serves both to permanently connect the piles and to prevent water passing through the joint between the piles. In the case of thin piles, the back of the said 85 edges, in which are located the key-ways, may be carried, as shown, beyond the face of the pile, giving additional space in which to locate said key-way.

Piles of such form are usually of such thickness as to make the use of a water jet desirable, if not imperative, during driving. Such water jet-pipe is a temporary expedient and can be conveniently placed in the key-way, being removed therefrom after the 90 95 100

driving of the pile and before the insertion of the permanent key. In order not to interfere with the operation of the pile driving hammer, it is desirable to have this jet-pipe 5 located beneath the top of the head of the pile. This is secured by a chase connecting with the key-way and extending to the face of the pile head.

Referring to the invention in greater particularity, and in connection with the said drawings, the reference numeral 1 indicates a pre-cast pile having a head 2 at the end thereof which in use is positioned at the top, and has a point 3 at the other or lower end. 10 The body or central portion 4 of the pile has one or more depressions 5 in a face thereof which lightens the pile and also reduces the friction necessarily resulting in driving the pile into place. The opposite side edges or 15 longitudinal margins of the pile are preferably off-set, thus providing an off-set edge 6 at one side of the pile and an off-set edge 7 at the other side of the pile. The off-set edges 6 and 7 preferably are upon opposite 20 sides of an imaginary plane extending in a flatwise direction through the middle of the body portion. Furthermore, the parts are preferably so constructed and arranged that when the piles are brought together the adjacent off-set edges of adjacent piles will 25 over-lap each other, as clearly shown in Figures 5 and 6. Key-ways 8 are shown formed in the overlapping faces of the off-set edges, these key-ways preferably being 30 re-entrant and extending the full length of the pile. Furthermore, the key-ways are so positioned that when the off-set edges are placed in their over-lapping positions, the key-ways in the overlapping edges will be 35 directly opposite to each other and opening 40 toward each other so as to receive a key 9. Said key preferably is enlarged at its edges to enter the enlarged or re-entrant portions of the grooves, and has a thin middle portion which will pass through the narrower 45 openings of the grooves. Before the keys are inserted, and during placing of the piles, it may be desirable to employ a wash pipe, the same being inserted in the groove tem- 50 porarily and withdrawn after the pile is finally placed. For accommodating such a wash pipe at the head of the pile, I provide a chase 10 from the outer surface of the pile to the groove, providing a depression below 55 the top surface or head of the pile for receiving the wash pipe 11 which is thus protected against crushing by the hammer or other means by which the pile is driven into place.

60 If so desired, a temporary key 12 may be employed for holding the piles together, this key being replaced at a later time by a permanent key of concrete or cement or other material which may be pre-cast or molded 65 directly in place as found most desirable. It

will be observed that my invention may be employed equally well on curvilinear piles as upon straight or flat piles. Furthermore, detail changes and modifications may be made in the construction and use of my invention, and I do not wish to be understood as limiting myself to the exact construction except as set forth in the following claims when construed in the light of the prior art. 70

Having thus described my invention, I 75 claim:

1. A construction of the character described, comprising in combination a plurality of pre-cast piles, each pile having an off-set edge off-set opposite to the edge of the 80 adjacent pile whereby adjacent edges of said piles will overlap, the overlapping edges having juxtaposed grooves opening toward each other, said piles also having transverse chases in the upper ends thereof running 85 into said grooves in the overlapping edges for reception of wash pipes, hollow temporary keys for securing said piles together by insertion in said juxtaposed grooves, and wash pipes in said temporary keys and in said 90 chases at a level below the upper end surface of the pile thereby avoiding interference with hammering the piles into place.

2. A pre-cast pile comprising a body portion having opposite stepped off-set portions 95 with one face of each off-set portion disposed intermediate of opposite side faces of the body portion, said off-set portions having re-entrant grooves therein with the depth of the 100 grooves transverse to the said opposite faces of the body portion, said re-entrant grooves adapted to receive keys for holding overlapping off-set portions of adjacent piles together.

3. A pre-cast pile comprising a body portion having opposite stepped off-set portions with one face of each off-set portion disposed intermediate of and parallel to opposite side faces of the body portion, said off-set portions having re-entrant grooves therein with the 110 depth of the grooves transverse to the said opposite faces of the body portion, said re-entrant grooves adapted to receive keys for holding overlapping off-set portions of adjacent piles together. 115

4. In a construction of the character described, the combination of a plurality of pre-cast piles, each pile having an off-set face off-set opposite to the off-set face of the adjacent pile and intermediate of opposed outside faces of the said piles so that the off-set portions of adjacent piles over-lap, the said faces of the over-lapping portions lying in juxtaposed relationship to each other and having juxtaposed re-entrant grooves there- 120 in opening toward each other with the grooves transverse to the exposed face of the pile, and a key in said juxtaposed grooves securing the piles against separating either in a direction in the plane of the piles or in a 125 direction perpendicular to the plane of the piles. 130

direction transverse to the plane of said piles.

5. In a construction of the character described, the combination of a plurality of pre-case piles, each pile having an off-set face off-set opposite to the off-set face of the adjacent pile and intermediate of and parallel to opposed outside faces of the said piles so that the off-set portions of adjacent piles over-lap, the said faces of the over-lapping portions lying in juxtaposed relationship to each other and having juxtaposed re-entrant grooves therein opening toward each other with the grooves transverse to the exposed face of the pile, and a key in said juxtaposed grooves securing the piles against separating either in a direction in the plane of the piles or in a direction transverse to the plane of said piles.
